US00D553477S

(12) **United States Design Patent** (10) Patent No.: **US D553,477 S**
Kuzukawa (45) Date of Patent: **** Oct. 23, 2007**

(54) **VIBRATION ISOLATOR MOUNT**

(75) Inventor: **Mitsuo Kuzukawa**, Saitama (JP)

(73) Assignee: **Fukoku Co., Ltd.**, Saitama (JP)

(**) Term: **14 Years**

(21) Appl. No.: **29/234,931**

(22) Filed: **Jul. 26, 2005**

(51) LOC (8) Cl. **08-05**

(52) U.S. Cl. **D8/354**

(58) Field of Classification Search **D8/354; 248/300, 589, 200**
See application file for complete search history.
